US00D851528S

(12) **United States Design Patent** (10) Patent No.: **US D851,528 S**
Bruder (45) Date of Patent: **** Jun. 18, 2019**

(54) **TRACKING DEVICE**

D777,050 S * 1/2017 Will D10/104.1
D799,353 S * 10/2017 Qu D10/104.2

(71) Applicant: **Tracktis GmbH**, Frankfurt (DE)

* cited by examiner

(72) Inventor: **Benjamin Bruder**, Frankfurt (DE)

Primary Examiner — George D. Kirschbaum

(73) Assignee: **TRACKTICS GMBH**, Frankfurt (DE)

(74) Attorney, Agent, or Firm — Defillo & Associates;
Evelyn A Defillo

(**) Term: **15 Years**

(57) **CLAIM**

(21) Appl. No.: **35/501,789**

The ornamental design for tracking device, as shown and described.

(22) Filed: **Apr. 28, 2016**

DESCRIPTION

(80) **Hague Agreement Data**

1.-3. Tracking Device

1.1 : Front

1.2 : Side

1.3 : Side

1.4 : Side

1.5 : Side

1.6 : Back

1.7 : Side

1.8 : Side

2.1 : Side

2.2 : Front

2.3 : Side

2.4 : Side

2.5 : Back

2.6 : Side

2.7 : Side

2.8 : Side

3.1 : Front

3.2 : Side

3.3 : Side

3.4 : Side

3.5 : Back

3.6 : Side

3.7 : Side
